UNITED STATES PATENT OFFICE.

MORTON SPENCE, OF SPRINGFIELD, ILLINOIS, ASSIGNOR OF ONE-HALF TO EARLE T. SPENCE, OF SPRINGFIELD, ILLINOIS.

INTERNAL-COMBUSTION ENGINE.

Application filed February 10, 1927. Serial No. 167,171.

The present invention is a modification and improvement of the invention disclosed in my application Ser. No. 135,383, engine-block and its cylinders, filed Sept. 14, 1926.

The purpose of the invention is to provide improved and effective means whereby the cost of production is materially reduced and the assembling, mounting and dismounting of the parts is greatly facilitated, without detriment to the security and safety of the structure as a whole.

A prime purpose is to provide a structure in which a single screw-ring is utilized to connect the cylinders with the engine-block.

15 The invention is illustrated in the accompanying drawing, to which reference is hereby made, and in which similar reference numerals and characters designate like parts in the several views.

20 I have shown and will describe the improvement as embodied in a single cylinder of an internal combustion engine; but it is obvious that the improvement may be applied to steam engines or gas engines without departure from my invention.

Figure 1 is a sectional view taken on the axis of a single cylinder body of a multi-cylinder of an internal combustion engine; Fig. 2 is a top view of the same structure that is shown in Fig. 1; Fig. 3 is an enlarged 30 fragmental sectional view showing clearly details of the connection of the assembled parts with each other; Fig. 4 is an elevation of the detached cylinder; Fig. 5 is a perspective view of the detached screw-ring; and Fig. 6 is a side view of a pin-wrench used to rotate the screw-ring.

The engine-block as a whole, is designated by the numeral 7. The cylinder body 40 is designated, as a whole, by the numeral 8, and the inner removable cylinder is designated, as a whole, by the numeral 9. The cylinder body has an internal circular flange 10 having a circular shoulder 12. A circular flange 13 near the upper end of the cylinder body has a recess or depression 14. The inner circular wall of the member 13 has internal screw threads 15.

The inner cylinder 9 has near its upper end 50 an integral flange 16 adapted to enter freely the depression 14 in the member 13. The inner removable cylinder also has an integral intermediate circular flange 17.

The screw-ring 18 has external screw threads 18^a adapted to engage the screw

threads 15 in the member 13. Holes 19 in the ring 18 are located to receive pins 21 of a pin-wrench 20 used to rotate the screw ring. A gasket 22 is interposed between the flange of the members 13 and 16 and a similar 60 gasket 23 is interposed between the members 10 and 17; to form a water-tight connection between the members.

The piston 24 is of usual construction and is adapted to slide in the inner or removable 65 cylinder and is moved by a piston rod 25 of usual construction.

To assemble the parts the inner cylinder 9 will be placed in the cylinder body with the flanges 16 and 17 supported on the gaskets 22 and 23 previously inserted on the members 13 and 10 and the screw-ring will be placed in the recess 14 and the pin-wrench will be used to rotate the screw-ring to cause it to bear firmly on the flange 75 16 and secure the assembled parts.

It is a common defect in reciprocating engines such as are used on automobiles that the throw of the crank causes lateral thrust against opposite parts of the internal wall of 80 the cylinder with the result that the wall instead of remaining truly circular wears in the form of an oval and this defect necessitates re-grinding of the cylinder. To overcome this defect I provide an inner removable cylinder which may be rotated by hand or any suitable means, to compensate for the wear, thus greatly prolonging the effective 85 life of the cylinder and avoiding the necessity for repeated re-grindings. This is an 90 important feature of my invention.

I am aware of the prior use of removable inner cylinders in the cylinder-bodies of engine-blocks I therefore do not claim broadly 95 that feature of construction.

What I claim as new and desire to secure by Letters Patent is:

1. In conjunction with a cylinder body having at its upper part a recessed internally screw-threaded member, said cylinder body 100 having also an upper internal circular flange and an intermediate circular member having a circular shoulder; a removable cylinder having external circular flanges co-operating with the respective inner flange-and-shoulder members of the cylinder body; washers interposed between the respective inner-flange-shoulder members of the cylinder body and the respective outer flanges of the removable cylinder; and an externally screw- 110

2
threaded ring engaging the screw threads in the recess of said upper flange member of the cylinder body and rotative to make a tight connection of the removable cylinder with the cylinder body.

2. In conjunction with an engine block having a circular bore an internal upper circular flange member and an intermediate circular flange-and shoulder member; a cylinder having an upper external flange member seating on said upper internal flange member of said block and an intermediate

external flange member seating on said intermediate flange and shoulder member of the block, to make a water-tight connection of the cylinder with the block, and a screw ring screwing into the upper end of the block and securing the cylinder in the bore of the block.

In witness whereof I have hereunto signed my name at Springfield, Ill., this 7th day of February, 1927.

MORTON SPENCE.
